UNITED STATES PATENT OFFICE.

WILLIAM M. MCKENZIE, OF DORCHESTER CENTER, MASSACHUSETTS.

SEPARATOR.

1,126,240.

Specification of Letters Patent.

Patented Jan. 26, 1915.

Application filed March 29, 1913. Serial No. 757,636.

To all whom it may concern:

Be it known that I, WILLIAM M. MCKENZIE, a citizen of the United States, residing at Dorchester Center, in the county of Suffolk and State of Massachusetts, have invented certain new and useful Improvements in Separators, of which the following is a specification, reference being had therein to the accompanying drawing.

10 This invention relates to separators especially adapted to be used for separating screw machine products from chips after the oil has been extracted therefrom; the object being to provide a separator which is so constructed that the finished products can be quickly separated from the shavings without handling the same, thereby overcoming the difficulties now existing in separating the products from screw machines.

20 Another object of the invention is to provide a separator in which an air blast is employed for separating the shavings from the articles produced on the screw machine wherein the shavings and articles are placed 25 in a receiving box from which they are forced onto a shaker for distributing the same, which is provided with a reticulated lower end allowing the air blast to act partly upon the shavings and articles before they 30 are discharged therefrom, whereby the lighter articles will be blown from off of the reticulated shaker and out of the falling mass of articles into another portion of the separator from which they are discharged 35 into a suitable receptacle; the finished articles or products being discharged at another point from the separator.

Another object of the invention is to provide a separator which is provided with 40 means for regulating the air blast in accordance to the nature of the products being separated; the separator having a sight opening through which the operator can watch the separating action of the air blast upon the 45 products and thereby regulate the same in order to prevent too heavy a blast which would cause the finished products to be blown with the shavings into the receiving compartment.

50 Another and further object of the invention, is to provide the separator with a finished product-receiving trough having a bottom formed of wood or other soft material in order to prevent the finished products 55 from being injured by the impact therewith in falling from the shaker.

Other and further objects and advantages of the invention will be hereinafter set forth and the novel features thereof defined by the appended claims.

60 In the drawings—Figure 1, is a side elevation of my improved separator partly broken away, showing the interior construction of the shaker and product-receiving trough; and Fig. 2, is a top plan of the separator.

65 Like numerals of reference refer to like parts in the several figures of the drawings.

In the drawing, 1 indicates a suitable base upon one end of which is mounted a casing 2 having an extended portion 3 forming a 70 compartment for receiving the shavings and like articles of the material placed in the separator, as will be later described. The extension 3 is provided with a reticulated end 4 and top portion 5 forming an exhaust for 75 the air and the lower end of said extension forms a receptacle which is provided with a suitable discharge opening, not shown, through which the shavings are adapted to pass and be caught by a suitable receptacle, 80 not shown.

The casing 2 is provided with a product-receiving trough 6 having a wooden bottom 7 inclined as shown, said trough being an extension of an air blast flue 8 and separated 85 therefrom by a reticulated partition 9, as clearly shown, for preventing the finished products from passing into the same over the outlet 10 which is provided with a discharge opening 11 through which the finished products are adapted to be discharged.

Extending into the casing 2 above the flue 8 is a shaker 12 provided with a closed top portion 13 and a reticulated lower end 14 which extends over the receiving trough 6; 95 said shaker being provided with transverse rods 15 mounted upon grooved rollers 16 in order to allow the same to be reciprocated easily in order to distribute the products and shavings over the bottom of the shaker so 100 that when they are discharged from the lower end the air blast will be allowed to have full force upon the same, as will be later described.

The base 1 is provided with standards 17 105 at its opposite end supporting a receiving box 18 having a discharge chute 19 extending into the shaker 12, as clearly shown in Fig. 1, through which the shavings and products are adapted to be forced manually 110 but of course, it is understood that various forms of receiving and distributing recep-

tacles could be employed for mechanically discharging the contents into the shaker.

Mounted on the base 1 between the uprights 17 is a blower 20 provided with a discharge 21 connected to the flue 8 by a coupling 22 which is provided with a reciprocating valve 23 to which is connected an operating rod 24; the upper end of which has a pivotal connection with an arm 25 fixed on a shaft 26 mounted in suitable depending brackets depending from the box 18. The shaft 26 at one end, is provided with a lever 27 having a hand lever 28 carrying a pin 29 adapted to co-act with a number of openings 30 of a plate 31 fixed on the side of the box 18 by means of which the lever 27 can be locked in its adjusted position, whereby the adjusted position of the valve can be maintained. It will be seen by this construction, 20 that the air blast can be regulated by operating the valve through the mechanism hereinbefore fully set forth so as to adjust the air pressure according to the kind of products being separated.

25 The blower 20 is provided with a fan shaft 33 having a drive pulley 34 at one end, which can be driven by a belt extending from a power shaft, not shown, or the same can be driven directly from a motor. However, the manner of driving this shaft forms no part of my invention.

Mounted in suitable bearings, not shown, is a drive shaft 35 which is driven by a twisted belt 36 passing over a pulley 37 carried by the shaft 35 and a pulley 38 carried by the shaft 35, the pulley 37 having a smaller diameter than the pulley 38 in order to reduce the speed of the shaft 35. The shaft 35 is provided with a pulley 39 carrying a belt 40 which extends transversely and passes over a pulley 41 carried by a counter-shaft 42 mounted in suitable bearings 43 and 44 carried respectively by the casing 2 and standard 17. The end of the shaft 42 is provided with a crank 45 carrying a wrist-pin 46 on which is mounted a pitman-rod 47; the free end of which is pivotally connected to a depending bracket 48 carried by the shaker 12. From the above, it will be seen that through the medium of the counter-shaft and driving connections, the speed of the drive shaft is reduced in order to prevent the shaker from being operated at an excess rate of speed.

55 The casing 2 is provided with a sight opening 49 in a hinged door 50 above the shaker, and the casing is provided with a light-receiving basket 51 in which an incandescent lamp is adapted to be placed in order to illuminate the inside of the casing so that the operator can inspect the separation so as to adjust the valve to regulate the air blast according to the material being separated.

65 The operation of carrying out the separa-

tion with a machine as set forth, is as follows: The products and shavings are placed in the box and the operator forces the same into the shaker, it of course being understood that the fan of the blower is being driven and that the shaker is being reciprocated simultaneously through the medium of the belts and pulleys and as the products are deposited upon the shaker by the reciprocation thereof, they are distributed and by the inclination of the shaker gradually work to the lower end upon the reticulated portion, at which point they are subjected to the air blast which blows the lighter particles or shavings into the receiving chamber; the particles failing to be lifted by the air blast, are then discharged from the shaker where they are subjected to the full blast of air and all of the lighter particles which have not previously been removed are blown to the upper portion of the casing and drop into the shaving-receiving compartment. The heavy particles of value, such as the finished products, drop into the inclined trough 6 upon the cushioned bottom 7 and by gravity, are discharged through the outlet 10 and discharge opening 11 into the suitable receptacles. As the separation is being carried out, the operator can watch the same through the sight opening 49 and regulate the air blast by adjusting the valve.

I claim:

1. In an apparatus for separating machine products, a longitudinally inclined supporting surface having a foraminated lower end impervious to the passage of any substantial amount of material therethrough and pervious to air to partially buoy the material in its passage thereover, means to feed products upon the upper end of said surface, means for reciprocating said surface to distribute and cause the products to move longitudinally thereon, means for passing an air blast through the foraminated portion of the supporting surface and past the edge thereof, and means to collect the separated products.

2. In an apparatus for separating screw machine products from chips, a longitudinally inclined supporting surface having a foraminated lower end impervious to the passage of any substantial amount of material therethrough and pervious to air to partially buoy the material in its passage thereover, means to feed products and chips upon the upper end of said surface, means for reciprocating said surface transversely to distribute and cause the material to move longitudinally thereon, means for passing an air blast through the foraminated portion of the supporting surface and past the edge thereof, to separate the products from the chips, and means to collect the products and chips.

3. In a pneumatic separating apparatus,

- the combination with a casing having a shaving-receiving compartment, an inclined product-receiving trough mounted within said casing, an air blast flue communicating 5 with the lower end of said trough, means for controlling the flow of air through said flue, and a shaker mounted within said casing having a reticulated portion impervious to the passage of any substantial amount of 10 material and pervious to air to partially buoy the material delivered from the edge thereof, said reticulated portion projecting into the trough and terminating intermediate the walls thereof.
- 15 4. In a pneumatic separator, the combination with a casing having a shaving-receiving compartment, of an inclined product-receiving trough mounted within said casing having an outlet at its lower end, an 20 air blast flue communicating with the lower end of said trough, and a shaking screen arranged above said trough having a foraminated portion extending into said trough and terminating intermediate the walls 25 thereof, over said outlet opening impervious to the passage of any substantial amount of material and pervious to air to partially buoy the material delivered from the edge thereof, and a valve arranged within said 30 air blast flue.
5. In a separating apparatus, the combination with an inclined trough having an outlet at its lower end, of an air blast flue arranged to force air through said trough, 35 a shaker arranged to deliver material into said trough having a foraminated portion at its lower end extending into said trough and terminating intermediate the walls thereof, and impervious to the passage of 40 any substantial amount of material and pervious to air from said flue.
6. In a separator, the combination with a casing provided with an inclined trough having a flue connected thereto, said flue 45 having an outlet arranged at the lower end
- thereof, a substantially vertical foraminated partition separating said flue from said trough at the lower edge of the outlet thereof, a blower connected to said flue, and a valve for controlling the passage of air 50 therethrough.
7. In a pneumatic separating apparatus, a trough having an outlet at its lower end, a supporting surface having a foraminated portion extending into said trough impervious to the passage of any substantial amount of material therethrough and pervious to air, means for passing a blast of air 55 through the trough and foraminated portion of the surface for blowing the lighter particles of said material falling from said foraminated portion out of said trough, means for collecting the heavier particles deposited in said trough, and means for collecting the lighter particles discharged by 60 said air blast from said trough.
8. In an apparatus for separating screw machine products from chips, a receiving trough, a receiving chamber arranged at the end of said trough, an air blast flue connected to said trough, a foraminated partition separating said trough from said flue, a shaker having a foraminated portion extending into said trough impervious to the 65 passage of any substantial amount of material therethrough and pervious to air to partially buoy the material in its passage thereover, means for reciprocating said shaker, and means for delivering upon the falling mass of material from said shaker and 70 against the foraminated portion of said shaker, an air blast for separating the lighter particles from the heavier particles.
- In testimony whereof I affix my signature in presence of two witnesses.

WILLIAM M. MCKENZIE.
